(57) CLAIM

The ornamental design for a bowl, as shown and described.

DESCRIPTION

FIG. 1 is a top perspective view of a bowl showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view taken along line 9-9 of FIG. 3.

The broken lines in the figures show portions of the bowl that form no part of the claimed design. The cross-hatching in FIG. 9 forms no part of the claimed design.

1 Claim, 7 Drawing Sheets
